METAL REMOVER FOR TOBACCO FEEDS

William C. Broekhuysen, Brooklyn, N. Y., assignor
to International Cigar Machinery Company, a
corporation of New Jersey

Application January 31, 1939, Serial No. 253,785

2 Claims. (Cl. 209—215)

This invention relates to metal removers for tobacco feeds, its main object being to clear a mass of short filler tobacco or similar material flowing in a comparatively thin stream over an electromagnetically vibrated hopper, of nails, screws and other ferrous objects which may have gotten into the material while being handled.

This object is achieved by magnetic attraction with a row of "Alnico" permanent magnets, which are formed of a ferrous alloy containing principally aluminum, nickel and cobalt as alloying ingredients and extending transversely across the tobacco stream, with their free poles a short distance ($\frac{3}{4}$ to 1") above a vibratory deck, or in the particular embodiment illustrated, the delivery lip of the feed hopper. The nominal composition of an example of "Alnico" is C 0.15%, Mn and Si 0.4% total, Al 12%, Ni 20%, Co 5% and remainder Fe. The above proportions are approximate and may vary considerably.

This device is rendered commercially practical for tobacco feeds handling scrap tobacco: (1) by the greatly increased effectiveness of the "Alnico" over ordinary permanent magnets, whereby they may be disposed far enough away from the hopper to permit free passage of the scrap thereunder; and (2) by the ideal condition for removing metal on the delivery lip of the feed hopper where the tobacco is traveling in a thin, wide stream, while being vibrated. The oblique vibration of the hopper imparts a hopping motion to the metallic objects, giving them a start in the direction of the magnetic pull and facilitating their removal.

In the accompanying drawing in which this invention is exemplified in the filler feed of a scrap bunch cigar machine such as described in the co-pending application of J. P. Durning, Serial No. 193,244, filed March 1, 1938:

Fig. 1 is a front elevation showing the delivery end of a vibrating feed hopper, with my improved magnetic separator installed therein; and

Fig. 2 is a sectional side elevation on line 2—2 of Fig. 1.

Referring to the drawing, the tobacco T in the resiliently supported obliquely vibrating hopper 3 is by the oscillating or stationary rakes 4 caused to emerge on the delivery lip 5 in a thin, wide stream T' which discharges through the opening 6, the flow of tobacco being periodically stopped by an electrically operated control plate 7 after a quantity sufficient for one bunch charge has been delivered.

At a midway point in the length of trough 8 there is supported, in a vertical position, a row of cylindrical "Alnico" permanent magnets 9, these magnets being vertically adjustable so that their free ends N hang a small distance above the top of the tobacco stream T'. A bar 10 attached to frame brackets 10 which support the shaft 11 of the control plate 7 is provided with vertical bores for the reception of the magnets 9 which are secured therein in any desired vertical position by set screws 12. The space between the tops of brackets 10 is enclosed by a cover 13. The hopper is equipped with an electric vibrator 14 which may be of the electromagnetic type shown in the Flint Patent 1,846,326, issued February 23, 1932, to impart oblique vibrations thereto of sufficient frequency to feed the filler tobacco through the magnets.

If any foreign objects of ferrous metal have accidentally entered the tobacco mass, they will be attracted and held by the poles of the magnets 9 and can be removed by the operator from time to time. Small magnets made of "Alnico" steel alloy have sufficient magnetic strength to attract small ferrous objects through comparatively large distances, the pull varying with the shape of the object, being the greater, the larger is the exposed surface area for a given weight. Thus, a $\frac{3}{4}$ " cylindrical "Alnico" magnet, 3" long, will pick up a $\frac{1}{8}$ " steel ball through a distance of $\frac{3}{4}$ ", a small tack, nail or screw, through a distance of 1", and a hair-pin through $1\frac{1}{2}$ to 2".

What is claimed is:

1. In a scrap tobacco feed, the combination with a vibratory hopper, of a set of rakes having their lower ends disposed adjacent the upper face of the bottom of said hopper to limit the flow of scrap tobacco therebetween to a thin stream, a series of magnets beyond said rakes in sufficient proximity to the upper face of the hopper bottom to remove ferrous objects from the entire depth of the thin stream emerging under the rakes and yet permit unobstructed passage of said stream, and means for vibrating said hopper obliquely toward and away from said magnets to form and advance the stream of tobacco thereunder, said hopper having a depressed lip whereover said magnets are disposed and said rakes being disposed at the juncture of said lip with the main portion of said hopper to maintain a supply of scrap tobacco behind said lip, said lip having a concave bottom and said magnets being disposed in perpendicular relationship to said bottom and individually adjustable

axially to adapt the same to the contour of the lip.

2. In a scrap tobacco feed, the combination with a vibratory hopper, of a set of rakes having their lower ends disposed adjacent the upper face of the bottom of said hopper to limit the flow of scrap tobacco there through to a thin stream, a series of permanent magnets beyond said rakes in sufficient proximity to the upper face of the hopper bottom to remove ferrous objects from the entire depth of the thin stream emerging under the rakes and yet permit unobstructed passage of said stream, and means for

vibrating said hopper obliquely toward and away from said magnets to form and advance the stream of tobacco thereunder, said hopper having a depressed lip wherever said magnets are disposed and said rakes being disposed at the juncture of said lip with the main portion of said hopper to maintain a supply of scrap tobacco behind said lip, said magnets being formed of a ferrous alloy containing aluminum, nickel and cobalt in the proportions commonly known as "Alnico."

WILLIAM C. BROEKHUYSEN.
